Patented Dec. 30, 1924.

UNITED STATES PATENT OFFICE.

WILLIAM KRAGIEL, OF PATERSON, NEW JERSEY.

COMBINED TOY AND ORNAMENT.

Application filed May 19, 1922. Serial No. 562,168.

To all whom it may concern:

Be it known that I, WILLIAM KRAGIEL, a citizen of the United States, residing at Paterson, in the county of Passaic and State of New Jersey, have invented new and useful Improvements in a Combined Toy and Ornament, of which the following is a specification.

This invention relates to a combined toy and Christmas tree ornament.

The principal object of this invention is the provision of a combined toy and ornament which is intended for use upon a Christmas tree and when so used, will add to its beauty in addition to being amusing.

Another object of this invention is the provision of a device consisting of a fan, means for rotatably securing said fan to the tip of a Christmas tree, candles arranged on the limbs of said tree for producing heat whereby the fan is revolved, and devices in the nature of toy aeroplanes depending from said fan.

With the above and other objects in view which will appear as the nature of the invention is better understood, the same consists in the improved construction and novel arrangements of parts which will hereinafter be fully described and particularly pointed out in the claim.

In the accompanying drawings which forms a part of this application.

Figure 1 is a side elevation showing the device applied to a Christmas tree.

Figure 2, is a detail sectional view.

Figure 3, is a plan view of the fan.

Referring more particularly to the drawings the reference numeral 10 denotes the toy or ornament in its entirety, the same consisting of a fan 11, having a hub or bearing 12. Radiating from the hub 12 are a plurality of vanes 13, the extremity of said vanes being secured to a ring or band 14. Cables 15, have one end connected to the band 14, the other end of said cables being

connected with a device 16, which in the present instance, is shown as a toy aeroplane.

A Christmas tree is shown at 17, the said tree consisting of the usual base 18, trunk 19, and limbs 20. Candles 21 are supported by the limbs 20. The tip of the tree has secured thereto a pintle 22, for rotatably supporting the toy or ornament 10.

In operation, the heat produced by the candles 21 tend to rise, thereby creating a draft sufficient to revolve the fan. In revolving, the aeroplanes 16, will be swung out around the tree, giving them a realistic appearance, which will greatly add to the beauty of the tree as well as being amusing.

While there has been shown and described one form of the invention, no limitations are necessarily made to the exact detail of construction, but that changes, modifications and alterations as come within the claim, may be resorted to when so desired.

What is claimed as new is:—

As a new article of manufacture a combined ornament and toy for Christmas trees comprising a member having a hub and a band encircling said hub, a plurality of radially disposed vanes connecting said hub with said band, a removable tubular pintle adapted to be attached to the tip of a Christmas tree and having a tapered end, a bearing in said hub for removably receiving said pintle for supporting said member above the tree, a plurality of devices suspended from said band by means of flexible cables and candles adapted to be suspended from said band by means of said member whereby the heat from said candles will co-act with the vanes of said member for causing the same to revolve about the tree and causing the figure to swing outward by centrifugal force as and for the purpose specified.

In testimony whereof I have affixed my signature.

WILLIAM KRAGIEL.
